INVENTOR

UNITED STATES PATENT OFFICE.

HAROLD M. BOWDOIN, OF TUCKAHOE, NEW YORK.

DESIGN FOR A CANDLE HOLDER.

60,603.

Specification for Design.

Patented Mar. 14, 1922.

Application filed September 25, 1920. Serial No. 412,877. Term of patent 3½ years.

To all whom it may concern:

Be it known that I, HAROLD M. BOWDOIN, a citizen of the United States, residing at Tuckahoe, in the county of Westchester and State of New York, have invented a new, original, and ornamental Design for a Candle Holder, of which the following is a specification, reference being had to the accompanying drawing, forming part thereof.

Figure 1 is a side elevation, Figure 2 is a top plan view of a candle holder, showing my design.

The design comprised in the invention consists of a metal saucer supported by legs which are extended on top of saucer and upwards to engage base of a wax candle.

What I claim is:

The ornamental design for a candle holder as shown.

In testimony whereof, I have signed the foregoing specification.

HAROLD M. BOWDOIN.
